CYLINDER RIDGE REAMER

Herbert A. Berkman, Chicago, Ill., assignor to
 Zim Manufacturing Company, a corporation of
 Illinois

Application May 13, 1948, Serial No. 26,857

6 Claims. (Cl. 77—2)

1 The present invention relates to small machines used for dressing cylinders of internal combustion engines, of the type that are inserted in a cylinder and have a cutter that revolves about the cylinder axis and is automatically fed lengthwise of the cylinder by means of a screw as the reaming proceeds; and it has for its object to produce a machine that shall be easy to adjust to cylinders of different sizes, over an unusually wide range, and that shall be very efficient and reliable in operation, and easy to operate.

Specifically considered, the invention may be said to have, for some of its objects, to produce a novel and superior type of drive for the screw that feeds the cutter and to provide a simplified anchoring means for the reamer.

The various features of novelty whereby the present invention is characterized will hereinafter be pointed out with particularity in the claims, but, for a full understanding of the invention and of its objects and advantages, reference may be had to the following detailed description taken in connection with the accompanying drawings, wherein:

Figure 1 is what may be termed a front view of a reamer embodying the present invention, applied to a cylinder that is shown in section; Fig. 2 is a top plan view of the reamer, with the cylinder appearing in transverse section; Fig. 3 is an axial section, showing only a fragment of the machine; Fig. 4 is a side view of the ledge for operating the cutter feed, detached from the supporting table for the reamer proper; Fig. 5 is a side view of the upper portion of the reamer, looking from a point to the left of Fig. 1, with the cylinder in section; Fig. 6 is a section on line 6—6 of Fig. 5; Fig. 7 is a view similar to Fig. 6, with the cover plate for a vertical star wheel omitted; Fig. 8 is a view looking up from the level of line 8—8 of Fig. 6; and Fig. 9 is a view somewhat similar to Fig. 7, showing a slight modification.

As in prior machines, the reamer proper is mounted on a flat support or table 1, which may conveniently be a thick disc cut away to form three equally spaced, stubby arms. Lying flat on the table is a rotatable slab-like part 2 that is held down by a headed bolt 3, as is the corresponding part in my prior Patent No. 2,136,350. The lower end of the bolt is screwed into a hub 4 on the under side of a thick, three-armed spider 5.

Spider 5 is held against rotation relative to the table by a long pin or stud 6 which is fixed to the table and extends down between two of the arms of the spider at their juncture. The spider may be provided with two little pins 7, arranged on

2 opposite sides of and in engagement with the lower end of pin or stud 6. Each arm of the spider contains a deep channel extending throughout the length of the arm and having a bottom wall 9 that slants outwardly and downwardly at an angle of 50°. In each channel is a shoe 8 in the form of a flat plate of a right angled triangular shape wherein the acute angles are both 45°, the tips, at the acute angles, being cut away.

10 The shoes are placed in the channels with their hypotenuses resting against the bottoms of the latter and one short edge of each bearing against the under side of the table. The vertical edge of each shoe contains a notch 11 in which a resilient ring 12, surrounding the whole, is seated; the ring being at all times under tension. Each spider arm contains a wide, deep notch 14, of distorted V shape, to leave the resilient ring free to remain in contact with the shoes at all times.

15 20 When bolt 3 is turned in one direction, the spider is drawn toward the table and the shoes are forced outward in the radial direction. The long, single slopes in the spider on which the shoes ride provide better bearings and a smoother action, and make possible a much simpler construction than that of the aforesaid patent.

25 Overlying part 2 and fastened thereto so that it may be adjusted radially of the axis of the tool is a large flat member or plate 15; this adjustability 30 being due to fastening member 15 to part 2 by a headed screw 16 that passes through a long slot 17 in member 15 and into part 2, as in prior constructions. Member 15 has a forwardly projecting ear 18 adjacent to one side edge. This ear extends

35 into a jaw 19 on one end of a horizontal arm 20 and, together with a pin 21, passing through ear and jaw, forms a hinge connection between members 15 and 20. Member 15 has a second ear, 22, at the front and at the side edge opposite that at 40 which ear 18 is located. Rising from ear 22 is a cam or eccentric pin 24 that lies in front of the free end of arm 20 and either holds the arm back or allows it to swing outwardly, depending on the angular position of the cam or eccentric; all of

45 which is, in principle, old construction. Behind the free end of arm 20 is a compression spring 25 which abuts at its front end against the arm at its rear end against a lip 26 rising from member 15. This spring at all times tends to swing the free 50 end of arm 20 forwardly or outwardly.

At about the middle of arm 20 is a column 27 that rises well above the remainder of the arm. In the front side of this column, and extending from a point near the upper end of the column to 55 a point near the lower edge of the arm 20, is a

wide, deep recess 28 of uniform width. In the rear portion of this recess is a vertical screw 29 having on its upper end, above the column, a knurled head or nut 30 by which it may be turned. On the lower end of the screw is fastened a horizontal five-armed star wheel 31. The head or nut and the wheel hold the screw against endwise movement. In the front or outer part of the recess is a block 32 that serves as a carrier for a cutter blade 34. The screw is in screwthreaded relation with the block or blade carrier, so that when the screw is turned the latter moves up or down as the case may be.

In the rear or inner side of arm 20 is a shallow recess 35 in which is mounted, for rotation about a radial axis, a vertical, five-armed star wheel 36 that projects down into mesh with star wheel 31 and well below the plane of the latter. When wheel 36 turns it drives wheel 31 and turns the screw.

In order to turn star wheel 36 I mount on table 1, at the outer end of one of its arms, a radial ledge 37 of considerable length. This ledge is high enough to project up into the path of the lowermost arm of the vertical star wheel, once during each revolution of member 15, the parts being so proportioned that, as the arm by which the vertical star wheel is being turned moves on over and past the ledge, the arm immediately ahead is swung down far enough so that it will strike the ledge at the end of the next revolution of the member 15. Thus it takes five revolutions of member 15 to turn the star wheels and screw through a single revolution and raise the blade through a distance measured by a single turn of the screw thread.

The impact of the vertical star wheel on the ledge and on the other star wheel is very gentle, so that the drive is smooth and noiseless.

When member 15 is adjusted radially, carrying the cutter blade nearer to or farther from the axis of the machine, the proper driving relation between the star wheel and the ledge is maintained, because of the length of the latter. This remains true as long as member 15 is not shifted outwardly farther than necessary to operate effectively in a cylinder of the largest diameter in which the anchoring means can be used.

The present invention is most advantageously employed for reaming automobile engine cylinders of the larger sizes, say up to about five inches in diameter. Some cylinders however, have still larger diameters, say six inches. In order to adapt the same machine to these very large cylinders, the machine has been designed so that it may easily be placed in condition to operate effectively in such cylinders as well as in the cylinders for which the reamer is primarily intended. However, it is impracticable to use the same anchoring means throughout that range; and I therefore provide a second, wider set of shoes (not shown), that may be substituted for those shown, when one of the largest cylinders is to be reamed. In this latter case, the ledge 37 must reach out farther to remain in the path of the vertical star wheel. To make this possible, the ledge is made in the form of a flat bar, rectangular in cross section, and is set edgewise into a deep radial groove or channel 38 in member 1. In one broad face of the bar are a plurality of depressions spaced apart lengthwise of the bar; two such seats, 39 and 40, being shown. A set screw 41, screwed in through the edge of member 1, is adapted to enter either of the two seats when brought into registration therewith to secure the

ledge in place. In the drawings, the set screw is engaged in seat 39, holding the ledge in what may be termed its retracted, normal position. When a very large cylinder is to be reamed, requiring the substitution of wider anchoring shoes: the set screw is loosened; the ledge bar is pulled lengthwise into its extended position with the seat 40 registering with the set screw; and the set screw is again tightened to secure the ledge in its new position.

As is usual in machines of the general type disclosed herein, the member 15 has a handle 42 rising therefrom at a point remote from the axis of the machine; this handle serving the double purpose of raising and lowering the machine in removing it from or placing it in a cylinder and of driving the machine in reaming.

A convenient way of mounting star wheel 36 is to make one of the wide walls bounding recess 35, in which this wheel is located, in the form of a removable cover plate; this plate providing a bearing for one end of shaft 23 that supports the wheel.

When the screw 29 is turned to adjust the cutter 25 in the vertical direction, it is theoretically possible to leave the wheel 36 in such a position that the point of the arm that engages the ledge 37 at the near upper corner when the wheel reaches the ledge; such arm acting as a strut between the 30 ledge and the supporting shaft for the wheel and locking the reamer against turning. To prevent this from occurring, a suitable indexing device may be provided to make it impossible for the star wheel to remain in an angular position that 35 leaves any one of its arms in the objectionable position. I have shown such a device in Fig. 9, the same comprising a spring-pressed ball 44 that projects a little into recess 35, while lying and movable radially of the wheel in the plane of the latter; the ball being so placed that whenever an arm of the wheel is brought into the unwanted position, another arm engages the ball which then acts as a cam to turn the wheel slightly and thus avert the danger of locking the reamer against turning.

In Fig. 9 there is illustrated another small change; the wall of the recess that is in the form of a detachable plate in the first form being made integral with column or post 27a, as would be preferable in the case die castings were used.

I claim:

1. In a cylinder reamer, a support, means to secure said support in an engine cylinder at a substantial distance from a ridge to be reamed, a member mounted on said support for rotary movements about the axis of the cylinder, a carrier for a cutting tool movable up and down on said member parallel with said axis, a screw on said member connected with the device to raise and lower it, a horizontal star wheel fixed on said screw near said support, a vertical star wheel on said member meshing with the first star wheel and adapted to turn the same, and a radial ledge on said support in the path of said vertical star wheel to turn the same through one step during each revolution of said member.

2. In a cylinder reamer, a support, means to secure said support in an engine cylinder at a substantial distance from a ridge to be reamed, a member mounted on said support so as to be adjustable radially of and rotatable about the axis of the cylinder, a carrier for a cutter movable up and down on said member parallel with said axis, a screw on said member connected with the carrier to raise and lower it, a horizontal star

wheel fixed on said screw near said support, a vertical star wheel on said member meshing with the first star wheel and adapted to turn the same, and a radial ledge on said support in the path of said vertical star wheel to turn the same through one step during each revolution of said member.

3. A cylinder reamer as set forth in claim 2, wherein said member is adjustable radially on the support.

4. A cylinder reamer as set forth in claim 2, wherein the support contains a radial groove in which the ledge is seated, the ledge has in a side thereof a plurality of seats spaced lengthwise of the same, and a set screw on the support is positioned to engage any one of the seats when that seats registers therewith.

5. In a cylinder reamer, a support, means to secure said support in an engine cylinder at a substantial distance from a ridge to be reamed, a member mounted on said support so as to be adjustable radially of and rotatable about the axis of the cylinder, an element mounted on said member for swinging movements from and toward said axis, a spring acting to swing said element away from said axis, a carrier for a cutter movable up and down on said element parallel with said axis, a screw on said element connected

with the carrier to raise and lower it, a horizontal star wheel fixed on said screw near said support, a vertical star wheel on said element meshing with the first star wheel and adapted to turn the same, and a radial ledge on said support in the path of said vertical star wheel to turn the same through one step during each revolution of said member.

6. A reamer as set forth in claim 1 wherein 10 the vertical star wheel has a series of radial arms, and which includes, additionally, a spring-pressed ball mounted in the path of the ends of said arms in position to engage an arm whenever another arm reaches a position that will 15 make it thrust in a direction radially of that wheel against the ledge upon reaching that ledge.
